Application November 8, 1940, Serial No. 364,798

1 Claim. (Cl. 196—9)

This invention relates to improvements in method of converting hydrocarbons and pipe still apparatus therefor. More particularly, the improvements relate to the heating of separate streams of hydrocarbons, the combining of said streams, and the heating of the resulting mixture in the same pipe still furnace.

This application is a continuation in part of application Serial No. 262,627, filed March 18, 1939, for "Pipe still furnace and method of heating hydrocarbons," now Patent No. 2,221,469.

The primary object of the present invention is to provide an improved pipe still furnace in which separate banks of tubes may be heated under different conditions.

Another object of the invention is to provide an improved method for heating hydrocarbons to effect their conversion into more desirable products.

These and other objects of the invention are attained by constructing a pipe still furnace with two or more radiant heating chambers of relatively great length compared with their width, providing heating tubes on the side walls of such chambers, and providing a firing pit opening into the bottom of each chamber and extending substantially the entire length thereof. The pipe still furnace is also provided with burners in the bottom of the pits, means for recirculating flue gases from the furnace back through the radiant heating chambers, and for distributing such gases over the tubes in the radiant heating chambers. Provision is also made for utilizing the combustion gases from the radiant heating chambers for heating a bank or banks of tubes mounted in a convection section of the furnace.

The important feature of the operation of the furnace is for example, the heating of one hydrocarbon stock on one side of the furnace to a very high temperature which may be considerably higher than the temperature used on the other side of the furnace for heating a different stock. While means is provided for individually controlling these temperatures, the temperature in the convection heating section of the furnace is controlled independently for example, by increasing the firing and circulation in one of the radiant chambers and at the same time not increasing the temperature in that chamber because of the high recirculation load. This control is particularly advantageous because it permits the use of the convection section at the desired temperature and the carrying out of an exothermic conversion reaction, since the large quantity of flue gas will act as a buffer to main-

tain the desired temperature either above or below that which might otherwise exist in the convection reaction tubes.

The invention will be further described with the aid of the accompanying drawings which show by way of example a preferred form of the invention, it being however understood that the invention is by no means limited to the specific embodiment illustrated. In the drawings:

10 Fig. 1 is a vertical cross sectional view of the improved pipe still furnace taken on the line 1—1 of Fig. 3, showing the relationship of the heating chambers and positions of the various tube banks.

15 Fig. 2 is a broken longitudinal vertical sectional view taken on the line 2—2 of Fig. 3.

Fig. 3 is a horizontal sectional view taken on the line 3—3 of Fig. 1.

20 Fig. 4 is an enlarged sectional view of a portion of the burner arrangement shown in Fig. 1.

The improved pipe still furnace of the present invention comprises a masonry structure composed of outside supporting walls secured to steel beams to which is also secured an inside refractory brick lining.

25 Referring to Fig. 1 of the drawings, the furnace comprises two radiant heating chambers 6 and 8 arranged in symmetrical manner, although a greater number of chambers may be employed if desired. These heating chambers are relatively long and narrow and provided with inside and outside rows of wall heating tubes for the heating of hydrocarbon stock to be converted. For example, a hydrocarbon stock such as gas oil, kerosene, naphtha or butane, may be supplied to the furnace at the desired pressure through a valved supply line 10 from which it passes through a series of preheated tubes 12 comprising the right half of the lower bank shown in Fig. 1. The hydrocarbon stock is then conducted by a connecting line 14 through an inside wall tube bank 16 mounted in the heating chamber 6, a connecting line 18, a side wall tube bank 20 and then through a roof bank of tubes 22, all heated by radiant heat in the chamber 6.

30 In accordance with the features of the invention a different stock from that heated in chamber 6 is supplied to the other side of the furnace at the desired pressure through a valved inlet line 24 and passed through preheating tubes 26, from which the stock is conducted through a connecting line 28, a wall tube bank 30 mounted in the heating chamber 8, a connecting line 32, an outside wall tube bank 34 and a roof bank 36. The tube banks 30, 34 and 36 are heated by radiant

heating in the chamber 8 and such heating may be to a higher or lower temperature than that to which the stock is heated in the tube banks of chamber 6. All of the tubes of the chambers 6 and 8 are supported in metal tube brackets or supports as shown in the drawings.

The hydrocarbon products passing through the tube banks 22 and 36 are mixed in a connecting line 38 and then distributed into a large convection tube bank 40 arranged between and separated from the heating chambers 6 and 8 by refractory bridge walls 42 adjacent the wall banks 16 and 30. The mixture of products in the line 38 and preferably distributed as shown into parallel tube arrangements so that hydrocarbon vapors for example may be heated for a relatively long period of time in the tube bank 40, which extends the full length of the furnace and in which the tubes are supported by tube sheets 44 (also used to support tubes 12 and 26). The products heated in the tubes of the tube bank 40 are collected in a line 46 and discharged from the furnace for further treatment.

The wall and roof tubes mounted in each of the radiant heating chambers 6 and 8 are supplied with radiant heat from long firing pits 48 which extend substantially the full length of the heating chambers. These pits are lined with high temperature refractory material and are preferably constructed with upwardly diverging side walls as shown which may have a smooth slope or may diverge by steps. The pits 48 are of substantial depth and the walls converge down to a series of burner units which are preferably made up in sections as shown in Fig. 3. The individual burners are preferably constructed as shown in Fig. 4, fuel being supplied thereto through pipes 52, and air for combustion being supplied to the passage way below the burner units or sections through air ducts 54.

As shown in Fig. 3, the burners for supplying combustion gases to the bottom of the pits 48 are divided into three sections, 56, 58 and 60. These sections are preferably supplied with fluid fuel such as combustible gas or oil under separate control, so that the heating effected by any section may be increased or decreased as desired.

Each burner section 56, 58 and 60 includes a plurality of burner openings 62 into which fluid fuel is injected and air induced. In each of the burner sections there is also a plurality of openings 64 for the admission of secondary air to the space above the burner section proper. The structure of the burner units is shown more in detail in the broken sectional view of Fig. 4 in which the burner is shown as comprising a steel supporting plate 65 containing the proper holes corresponding to the openings 62 and 64, the lower portion of the openings 62 being formed by short flaring tubular sections of cast iron 68 set in the holes in the steel plate 65. The burner sections are then formed by filling in around the cast iron elements 68, and removable cores set in openings 64, with plastic refractory material to form the flaring outer portion of the openings 62. The whole unit or section of the plate 66 which may be from 4 to 8 feet in length, is cast, dried and fired.

Fluid fuel and air for combustion is supplied to the lower portion of the openings 62, the former from the fuel pipe 52, by means of branch pipes 70 which terminate in burner tips 72, which in turn are provided with braces 74 for positioning the burner tips with respect to the openings 62.

As combustion takes place in the pits 48, the combustion gases expand into the increasing cross sectional area of the burner pits, the diverging walls of which permit the expansion of the gases during combustion without substantially increasing their velocity.

The high temperature combustion in the pits 48 heat the diverging walls thereof to extremely high temperatures so that they constitute radiant heating surfaces which reflect upon the tubes of the wall banks 16, 20, 30 and 34 and of the roof banks 22 and 36. It will be noted that the walls of the combustion pits are so arranged that the wall tubes closest to the pit are exposed to a smaller area of the radiant pit walls than are the tubes at greater distances. This arrangement prevents overheating of the tubes closest to the combustion pits and at the same time provides adequate radiant heating surface for the tubes at greater distances. The radiant surfaces may be actually arranged so that all wall tubes as well as the roof radiant tubes will be heated to approximately the same degree.

The combustion gases discharged from the combustion pits 48 flow up through the radiant heating chambers 6 and 8 and over bridge walls 42 into the convection heating chamber where they heat the reaction tube bank 40 and the pre-heating tubes 12 and 26. A considerable part of the heat in the combustion gases is removed by the tube banks 40, 12 and 26, after which the gases then flow through end discharge ducts 76 into a passageway 78 (Fig. 3) from which they pass to a stack 80 or to a recirculation flue gas fan 82, or both. The ducts 76 are provided with control damper 84 which may be operated by handles 86 to control the proportion of flue gas discharged through each duct.

One of the important features of the present invention is the recirculation of flue gases discharged from the furnace back into the radiant heating chambers to aid in controlling the heating of the roof tubes and also the convection tubes. The gases to be recirculated are picked up by the fan 82 which is operated by a motor as shown in Fig. 3, and conducted through a main passageway 88, then into distribution headers 90 for the radiant heating chambers 6 and 8. From the headers 90 the recirculated hot flue gases are passed to distribution ducts on each side of the burner pits which extend beneath the wall tubes 16, 20, 30 and 34. The means for distributing the flue gases under each of the wall tube banks is illustrated in detail in Fig. 2 in which flue gases are conducted from each header 90 through separate distribution ducts 92, 94 and 96 which lead respectively to the front, middle and far end sections of the furnace. The proportion of flue gas introduced into each of these ducts is controlled by a damper 98. The flue gas passed through the ducts 92, 94 and 96 (Fig. 2) is distributed directly under the vertical row of wall tubes 34 through openings between fire brick 100 which are mounted in spaced relation directly below each of the vertical rows of wall tubes 34. The same arrangement is used for the other wall tubes 16, 20 and 30. The dampers 98 for controlling the supply of recirculated flue gas to ducts 92, 94 and 96 for both sides of each of the radiant heating chambers 6 and 8 may, if desired, be operated together by handles 102, as shown in Fig. 3. The dampers 98 for any vertical tube bank may be operated individually to effect any desired control.

Instead of dividing the radiant heating cham-

bers lengthwise into three sections with respect to return of the flue gases (which correspond generally to the three-burner sections 56, 58 and 60), each heating chamber may be divided into any desired number of sections provided with individual control. The structure as shown provides for the control of the recirculated flue gas introduced into any section of each radiant heating chamber by suitable manipulation of the dampers 98. For example, all of the flue gases returned to one of the radiant heating chambers may be introduced through the opposite passageways 96 or the dampers 98 may be adjusted to exactly proportion the returned flue gases to the whole length of the heating chamber through the passages 92, 94 and 96 which would be impossible if the furnace were not divided into sections for control of flow. The burner sections 56, 58 and 60 mounted in the bottom of each combustion pit are preferably operated by sections corresponding to the sections of control provided for the return of flue gases.

In heating the vertical wall tube banks in either heating chamber 6 or 8, the burner sections may be operated for example by supplying most of the fuel to the section 56 and only moderately firing the burner sections 58 and 60. In such a case the flue gases returned to the chamber may be introduced to the greatest extent through ducts 92 for that chamber by controlling the dampers 98 thereto. This type of operation will provide adequate protection for the portions of the tubes opposite the burner section 56. The heating of this particular chamber may be further controlled by closing the flue gas outlet 76 nearest the fan 82 in Fig. 3, so that most of the flue gas is discharged from the opposite end of the furnace to that of highest temperature. This will cause a flow of combustion gases longitudinally in the radiant heating chamber and supply more heating gases to the sections toward the stack end of the convection heating chamber containing tube banks 40, 12 and 26.

Various other modifications may be made in the operation of the burner sections and flue gas return ducts to accomplish any desired result or effect, and one of the radiant heating chambers may be operated to supply considerably more heat or a higher temperature than the other if desired or necessary in carrying out a particular conversion operation.

As an example of the use of the improved pipe still furnace arrangements in the conversion of hydrocarbons to produce a high anti-knock gasoline, a charging stock of straight run gas oil is introduced at a pressure of about 600 lbs. per square inch through the line 10, preheated in tubes 12, and then subjected to conversion in tube banks 16, 20 and 22, so that the products are discharged into the mixing line 38 at a temperature of about 980° F. The heating operation carried out in the radiant heating chamber 6 is preferably such that the gas oil is heated rapidly to an active cracking temperature in the tube bank 16 and then subjected to conversion in tube banks 20 and 22 to provide a maximum of unsaturated olefinic type hydrocarbons by the time the products enter the mixing line 38.

During this operation in the radiant heating chamber 6 a "butane" fraction is converted in radiant heating chamber 8. In this operation a "butane" fraction composed mainly of butane but which may include propane and a small proportion of pentane, is introduced at a pressure of about 600 lbs. per square inch through the

line 24, preheated in tubes 26, and rapidly heated to a temperature of about 1050° F. in wall tube banks 30 and 34. The temperature of the butane fraction is further raised to about 1100° F. in the tube bank 36, so as to effect substantial dehydrogenation by the time the products enter the mixing line 38.

In the line 38 the hydrocarbon products containing very substantial proportions of unsaturated hydrocarbons, are mixed and then distributed into the tube bank 40 where alkylation and polymerization reactions take place to produce a product boiling within the gasoline range which contains from 25% to 85% of aromatic hydrocarbons. Many of these hydrocarbons have side chains of from 1 to 6 carbon atoms. The temperature in the tube bank 40 is controlled to substantially maintain the reaction conditions constant at a temperature of about 1025° F. or somewhat lower, depending upon the aromatic content desired in the final product. The high temperature products are discharged from the tube bank 40 through the transfer line 46 into suitable apparatus for segregating the desired products. Under certain conditions, the high temperature products in the line 46 may be conducted into a reaction chamber for further conversion either with or without a catalyst. In any case, the products discharged through the line 46 are subsequently fractionated in the desired manner to separate out the desired high anti-knock gasoline or motor fuel fraction.

In the operation described above, the temperatures maintained in the radiant heating chamber 8 are substantially above those maintained in chamber 6. This may be accomplished by increasing the firing rate of the burner sections for the chamber 8. Flue gas recirculated along the wall tube banks in both radiant heating chambers may be controlled to prevent substantial impingement of high temperature gases from the firing pits. Furthermore the temperature in the convection bank 40 may be controlled independently by increasing or decreasing the firing rate in one of the furnace chambers and increasing or decreasing the flue gas recirculation rate therein. An increase in the circulating flue gas load has its primary effect upon the conditions maintained in the convection bank 40 which may be controlled so that the flue gases either act to slightly raise the temperature of the hydrocarbon products under reaction or to actually decrease the temperature of the hydrocarbon products and prevent undue rise in temperature because of exothermic reactions which may take place in the hydrocarbons being treated.

Various modifications may be made in the pipe still furnace and in its operation to carry out the desired conversion reactions without departing from the spirit and scope of the invention as defined by the accompanying claim.

Having thus described the invention in its preferred form, what is claimed as new is:

65. A process for converting hydrocarbons for the production of hydrocarbons of high antiknock value in a pipe still furnace provided with radiant heating chambers separated by a convection heating chamber, said chambers being provided with tubes for heating the hydrocarbons to be converted, which comprises separately and independently heating relatively low boiling and relatively high boiling stocks in said radiant heating chambers, said stocks being substantially completely vaporizable under the temperature and

pressure conditions maintained in the tubes of said radiant heating chambers, heating the higher boiling stock to a cracking temperature for a sufficient time to convert it to a product containing substantial proportions of unsaturated olefinic hydrocarbons, heating the lower boiling stock to a substantially higher cracking temperature and converting said lower boiling stock into constituents containing substantial proportions of olefinic hydrocarbons, mingling the conversion products of said heating operations carried out in said radiant heating chambers and conducting the resulting mixture through the tubes in said convection heating chamber and therein interpolymerizing and reacting the hydrocarbon conversion products to produce a substantial proportion of constituents boiling within the motor fuel range and which are of high antiknock character, maintaining a substantially constant temperature in said convection heating chamber, independently heating the hydrocarbons in said radiant heating chambers by radiation from a combustion heating means in each chamber, combining the high temperature products of combustion from said radiant heating chambers and passing them over the heating

tubes in the convection heating chamber to effect the desired reactions therein, maintaining a substantially higher temperature in the radiant heating chamber in which the lower boiling stock is heated than in the other radiant heating chamber, and simultaneously and independently controlling the temperature maintained in the convection heating chamber without substantially changing the temperature maintained in said radiant heating chambers and preventing impingement of high temperature combustion gases on the heating tubes in said higher temperature radiant heating chamber by distributing regulated quantities of relatively cool recycled flue gases over the heating tubes in said higher temperature radiant heating chamber and conducting the flue gases passed over said tubes into said convection heating chamber along with the combustion products from said higher temperature radiant heating chamber, whereby a substantially constant temperature is maintained in said convection heating chamber regardless of the high temperatures in said radiant heating chambers.
